RANGE APPARATUS

Hursle E. Cossin, Detroit, Mich., assignor to Nash-Kelvinator Corporation, Detroit, Mich., a corporation of Maryland

Application July 29, 1942, Serial No. 452,744

1 Claim. (Cl. 126—374)

The present invention pertains to an electric range, and more particularly to construction of a cooking well used therein.

It is an object of the present invention to provide a well having insulated walls in which is suspended a cooking vessel and having an arrangement for controlling a heating element positioned in the well so as to maintain uniform a selected cooking temperature during the entire cooking process.

It is another object of the present invention to provide a pressure responsive device for controlling a heating element positioned in a cooking well, which is responsive to the temperature of the heated air circulating about the cooking vessel set within said well.

The invention itself, however, both as to its organization and its method of operation, together with additional objects and advantages thereof, will best be understood from the following description when read in conjunction with the accompanying drawings, in which:

Fig. 1 is a front elevational view of a range embodying features of the present invention;

Fig. 2 is a view taken along line 2—2 of Fig. 1;

Fig. 3 is an enlarged view taken along line 3—3 of Fig. 2;

Fig. 4 is a cross sectional view with parts broken away along line 4—4 of Fig. 2;

Fig. 5 is a fragmentary top plan view of the invention with parts broken away and parts shown in section;

Fig. 6 is a fragmentary enlarged cross sectional view taken along line 6—6 of Fig. 4;

Fig. 7 is a fragmentary enlarged cross sectional view taken along line 7—7 of Fig. 5;

Fig. 8 is a fragmentary enlarged cross sectional view taken along line 8—8 of Fig. 5;

Fig. 9 is a fragmentary enlarged cross sectional view taken along line 9—9 of Fig. 2;

Fig. 10 is an enlarged cross sectional view taken along line 10—10 of Fig. 2;

Fig. 11 is a cross sectional view taken along line 11—11 of Fig. 9; and

Fig. 12 is a diagrammatic view of the wiring diagram used in the present invention.

Shown in the drawings is an electric range 20 comprising a shell or casing 22 supported on base 24, and a table top 26 supported upon and secured to the casing 22. The table top has an upwardly extended back portion 27.

Formed in the table top 22 are openings 38 each having its marginal rim insetted to form a ledge 32 for support of surface heating element or unit 34. Each unit is connected in an elec-

trical circuit (not shown) with a respective manually operated switch 36 on panel 37 for controlling the current to the unit.

Formed in the top 22 is an enlarged opening 40 having its marginal rim insetted to form a ledge 42 upon which is supported by its rim 44 a depending vessel 45 forming a well 46. The vessel comprises an outer shell 49, an inner shell 50 set in spatial relation to shell 49 to permit heat insulation material 52 to be packed therebetween, and a bottom wall 54. The inner shell 50 is formed in two sections, an upper portion 56 and a lower portion 57 whose ends telescope at about midway in the well and are secured together by weld, or the like. The upper portion 56 is formed with the rim 44 against which abuts one end of the outer shell 49. Lugs 59 are secured by weld at spatial intervals to the lower portion 57 of the inner shell adjacent its bottom edge. The bottom wall 54 is attached by screws to the lugs 59 and serves as a cap for the inner and outer shells.

The vessel 45 is secured to the table top by means of an L-shaped bracket 61 attached to the outer shell 49 and having one leg 62 engage the underside of ledge 42 to prevent lifting or removal of the vessel through opening 40. To hold the vessel stationary and prevent rotation an upwardly extending arm 63 is secured by weld to the outer shell having its free end engageable in a recess 64 formed in the ledge 42.

Set within the wall 46 is a container or kettle 66 having a rim 67 adapted to rest upon the rim 44 for dependingly supporting the kettle within the well. The kettle is provided with a suitable cover or lid 68. Handles 70 are pivotally mounted to the kettle to assist in lifting the kettle out, or inserting the kettle into the well 46.

The kettle is slightly spaced from the sides of the well to permit air circulation. The air is heated by electrical coils 72 wound and set in grooves formed in the insulation disk 74 secured by bolt and nut 76 to the bottom wall 54. The ends of coils 72 are bindingly secured to terminal post which are connected by conductor strips 77 to terminal block 78. A shield plate 80 is secured to the bottom wall 54 to extend over and protect the conductor strips and terminal post.

A wire 82 connects one side of the coils 72 to one side of a thermostatic switch 84. The other end of the coils 72 are connected by wire 88 and with wire 90, connecting the other side of the thermostatic switch 84, to a suitable source of electrical energy.

The thermostatic switch is provided with a

tube 100 having its end secured in a recess 102 formed in the inner shell 50. The recess extends circumferentially about the well 76, and is formed by depressing the lower shell 57 at a point where it telescopes with the upper shell 56. The shell 56 extends slightly over the recess so as to form a pocket or trap for the air circulating upwardly from the heating coils to contact the tube. The tube extends preferably about one-half the distance about the circumference of the well and is secured by tabs 104 which are punched from the shell 57. Openings 106 is formed in the outer shell to permit insertion of a tool for pressing the tabs 104 under the tube.

The thermostatic switch 94 is secured to a panel 110 affixed to the casing 22. A shaft 112 extends from the switch through the panel 110 and having affixed thereon an adapter extension 113 which projects through front panel 37. Fixedly secured on the adaptor extension is a knob 116. A rotation of the knob 116 rotates the shaft to effect variation in the pressure differential required to operate the switch mechanism within the casing 94. The thermostatic switch is not shown in detail in that it may be of any of the types known to the art. Stops are provided for the switch comprising a screw 119 carried by the adaptor 112 adapted to abut the turned edge 120 of the spring arm 122 when the switch is fully opened, and abut the arm 124 when the switch is fully closed. A notch 130 formed in the adaptor is engaged by arm 122 to hold the switch in open position. The arms 122 and 124 are bent from plate 126 which is secured to the panel 110.

A signal light 134 is secured above the thermostatic switch 94 connected across the line from wire 92 to wire 95 to indicate when the current is flowing to the coils 77. The signal light is viewed through opening 135 in panel 37.

The tube 100 is filled with suitable liquid or gases which is sensitive to the variation in temperature of the circulating air in the cooking well to effect a corresponding change in its pressure to operate the switch mechanism in casing 94 to either close or open the electrical circuit dependent upon a rise or fall of the air temperature from the predetermined selected temperature. Graduations are marked on the panel 37 to determine the degree of rotation of the knob 116 for a setting to a desired temperature.

By placing the tube 100 in direct contact with the heated air circulating about the cooking vessel or kettle there is maintained a more uniform cooking temperature. The capillary tube is instantaneously responsive to the air temperature to effect immediate operation of the switch mechanism upon a slight variation of air temperature.

Shielding the tube 100 within the recess by the overhanging of the wall 56 the kettle may be readily removed from or inserted into the well without fear of injury to the capillary tube.

While I have shown and described the preferred form of my invention, I do not wish to limit myself to the precise details as shown, but wish to avail myself of such variations and modifications as may come within the scope of the appended claim.

I claim:

In a cooking well having spaced inner and outer side walls and a bottom wall, heat insulation between said spaced side walls, said inner side wall having upper and lower sections in telescoping arrangement, the lower section having a depressed portion forming with the telescoping upper section a pocket, said pocket being in open communication with the well and a control element positioned in said pocket.

HURSLE E. COSSIN.
